(57) **CLAIM**

The ornamental design for a pattern on wall portion of elevator, lift, or hoist, as shown and described.

DESCRIPTION

The patent or application file contains at least one drawing executed in color. Copies of this patent or patent application publication with color drawing(s) will be provided by the Office upon request and payment of the necessary fee.

The FIGURE is an orthographic view of a pattern on wall portion of elevator, lift, or hoist according to our new design. The broken-lines illustrate environmental structure and form no part of the claimed design.
